UNITED STATES PATENT OFFICE

THOMAS F. CUNNINGHAM AND ARTHUR H. GIFFORD, OF BOONTON, NEW JERSEY

PIPE WRENCH

Application filed July 18, 1929. Serial No. 379,094.

The pipe wrench of the present invention, while capable of general utility is more especially intended for use in connection with relatively large pipes, say from four inches 5 to two feet and upwards in diameter.

An object of the invention is to provide a wrench which is substantially proof against slipping or twisting when in use and which thereby serves to effectively apply the desired 10 turning force always at right angles to the pipe.

Another object is to provide a wrench of rugged, durable construction capable of use on a widely varying range of pipe sizes, and 15 one which, while assuring full power transmission to the pipe, is effective to minimize injury to the pipe even when maximum pressures are exerted.

Another object is to provide a wrench having an effective downstroke action and, therefore, particularly applicable to work on over-head pipes or pipes located in comparatively inaccessible places. One important result obtained by the downstroke action 25 is that the weight of the handle is always opposing the torque resistance of the pipe, whereas with an upstroke handle the weight of the handle and the torque resistance are cumulative forces which the operator must 30 overcome.

Another object is to provide a wrench so designed that the slightest reverse pressure on the handle will disengage the wrench from the pipe, so that moving the wrench 35 from one gripping position to another is accomplished with a minimum of effort. The wrench is quick to engage the work as the handle is moved one way and equally quick to release it upon retrograde handle movement.

In a preferred embodiment of the invention the wrench is of the type employing a contractile, articulated pipe encircling member, such as a chain, but contrary to prior 45 practice both the shoe of the wrench handle and the anchor link of the chain are toothed or serrated to cooperatively grip the pipe in a powerful manner which entirely obviates the danger of slippage. There is thus provided a wrench having one or more pairs of

55 pipe gripping or biting elements engaging in circumferentially spaced sections of the pipe surface and acting together to twist the pipe and prevent slipping of the tool as the torque is applied to the work.

Preferably also both the toothed anchor link of the chain, and the pipe engaging shoe are readily reversible to bring unworn surfaces into play whereby a double life is insured for both of these elements.

60 In a preferred construction the shoe consists of a pair of parallel toothed disks, with a spacer unitary therewith thus affording a groove to straddle the lower edge of the handle which may be connected in place by a bolt. The bolt may be selectively passed through either of two pairs of diametrically aligned openings in the shoe whereby the shoe is reversible. The anchor link of the chain is of arcuate form, having openings at 65 its ends for pivotal engagement with the ends of the shoe bolt and with an adjacent chain link respectively. Since the openings at both ends of the anchor link are identical this link may also be reversed when one end thereof becomes worn.

70 The invention may be more fully understood from the following description in connection with the accompanying drawings, wherein:

75 Fig. 1 is a plan view of our improved wrench showing the same in operative relation to a pipe,

Fig. 2 is a side elevational view thereof with the pipe in section,

Fig. 3 is a vertical sectional detail on the line 3—3 of Fig. 2, and,

Fig. 4 is a view similar to Fig. 2, but showing the wrench applied to a pipe of much smaller diameter.

80 In the drawings we have used the reference numeral 10 to designate the handle of the wrench which may be of flat and relatively heavy bar stock, tapering in width toward its free end and being of slightly reduced thickness at 10^a adjacent its wider working end.

85 The shoe or fulcrum member which is fixed upon the end of the handle may conveniently include a pair of relatively heavy

disks 11 spaced apart a distance equal to the thickness of the handle portion 10^a and rigidly connected together by a central web block 12 of elongated formation having flat 5 sides and having its axis disposed along one of the diametric axes of the disk. Preferably as shown in Fig. 3, the disks 11 and the block 12 are a unitary forging or casting or are welded together of originally separate pieces. Pairs of aligned openings 13 and 14 are provided in the disks between the disk edges and the web block, these openings being preferably arranged upon a common diametric axis at right angles to the 15 axis of the web block. When the disks which constitute the shoe are positioned to straddle the lower edge of the handle lever, and one of the flat sides of the web block abuts the lower edge of the lever, one of 20 the other pair of openings 13, 14 may be aligned with a corresponding opening 15 in the wrench handle and the shoe may be secured in place by a bolt 16 passed through the aligned openings 13, 15 or 14, 15 as the 25 case may be.

The articulated pipe embracing member may be a chain of more or less conventional construction, each link as best seen in Fig. 1 comprising a pair of spaced parallel plates 30 18 connected to the straddled or straddling plates of an adjacent link by a common pivot pin 19. The anchor link of this chain, however, is of special formation comprising relative long massive arcuate plates 20, the concave edges of which are toothed or serrated at 21. The plates of the anchor link are connected by a pivot pin 19^a to the adjacent link 17 of the chain, spacer members 22 being provided if necessary to compensate for 40 the distance between the plates of the anchor link since the latter preferably straddle the shoe 11, 12 and their ends are pivoted on the projecting ends of the bolt 16.

In operation the free end of the chain is 45 wrapped around the pipe 30 and one of the chain links is engaged with an upstanding lug 23 on the top of the lever end. Thus with the parts in Fig. 2 the normal gravity action of the lever will cause the lever and shoe to 50 rock about the point of contact 25 between shoe and pipe as a fulcrum in which movement the lug 23 is drawn in a direction to tighten the chain 17 about the pipe and pull the anchor link 20, 20 into firm engagement 55 with the pipe. In other words, with the tool in the position of Fig. 2 the weight of the lever causes the tool to firmly grip the pipe and the weight of the lever is effectively applied in a direction to oppose the torque 60 resistance of the pipe. As the free end of the lever is grasped and manually pulled down the pipe is caused to turn since the lug 23 being more remote from the fulcrum point 25 than the bolt 16, swings through a greater 65 arc with resultant tendency to tighten the

chain and through it apply a twisting movement to the pipe.

As the lever is lifted up lever and shoe again rock as a unit about the fulcrum 25 and in this rocking motion movement of the lug 23 is through a longer path than pivot 16, causing slack in the chain and instantaneous release of the pipe 30.

Thus the lever may be oscillated back and forth with substantially no lost motion at the start of its working stroke and with no special effort needed to cause release at the start of the idle stroke other than the power required to lift the weight of the lever itself.

When wear occurs on the teeth of the disks 11 or on the anchor links of the chain these elements may be conveniently reversed to bring new unworn teeth into engagement with the surface of the pipe. Reversal of the shoe is accomplished by merely removing the bolt 16 and inverting and replacing the shoe. Reversal of the link plates 20 is accomplished by removing both the bolt 16 and pivot pin 19^a and then reconnecting these plates to the shoe and chain respectively with their ends in reversed position, that is to say, with the ends that have been previously attached to the bolt now connected to the pivot pin.

Figure 4 requires no special description, but is illustrative in a self-evident manner of the fact that the wrench is applicable conveniently to a large range of pipe sizes, it being here shown applied to pipe 30^a of much smaller diameter than the pipe 30.

Due to the four-point biting or gripping contact, a wrench constructed in accordance with the present invention cannot slip or turn sidewise and always exerts its pressure at right angles. The pressure of the wrench is well distributed reducing the scarring of the pipe when a maximum pressure is exerted. The circular design of the shoe reduces manufacturing costs both in casting and finishing, permits the wrench to engage the work at any point on the circumference of the shoe and permits reversibility discussed above. The wrench is readily adaptable to a large size range of pipes and is comparatively light in weight.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described our invention, what

we claim as new and desire to secure by Letters Patent of the United States is:—

1. In a pipe wrench, a handle lever, a shoe fixed to the end of the lever and adapted to provide a fulcrum at its point of engagement with a pipe, an articulated flexible device to encircle the pipe, pivotally connected at one end to the lever, a member on the handle to be selectively engaged with one of the free links of the articulated device, said member being fixed on the handle at a greater distance from the fulcrum point than the distance of the pivot from the fulcrum point, the shoe comprising a pair of spaced disks to straddle the lever and movable to present different fulcrum surfaces to a pipe, a web block rigidly connecting the disks and including a flattened portion to lie against the edge of the lever. 70
2. A pipe wrench including a handle lever, a fulcrum shoe fixed at the end of the lever, the shoe comprising a pair of rigidly connected spaced disks lying on opposite sides of the lever and movable to present different fulcrum surfaces to a pipe, a chain pivoted at one end to the lever, and an anchor lug on the lever to detachably engage any free link of the chain after the chain has been passed around a pipe. 75
3. A pipe wrench including a handle lever, a fulcrum shoe fixed at the end of the lever, the shoe comprising a pair of rigidly connected spaced disks lying on opposite sides of the lever and movable to present different fulcrum surfaces to a pipe, a chain pivoted at one end to the lever, and an anchor lug on the lever to detachably engage any free link of the chain after the chain has been passed around a pipe, the means for rigidly connecting the disks of the fulcrum shoe comprising an integral elongated web block, the axis of which is coincident with one of the diametric axes of the disks, said block providing flat sides for engagement with an edge of the lever. 80
4. A pipe wrench including a handle lever, a fulcrum shoe fixed at the end of the lever, the shoe comprising a pair of rigidly connected spaced disks lying on opposite sides of the lever and bolted thereto, a chain pivoted at one end to the lever, and an anchor lug on the lever to detachably engage any free link of the chain after the chain has been passed around a pipe, the means for rigidly connecting the disks of the fulcrum shoe comprising an integral elongated web block, the axis of which is coincident with one of the diametric axes of the disks, said block providing flat sides for engagement with an edge of the lever, the disks having pairs of aligned openings therein arranged at opposite sides of the web block and on a common diametric axis at right angles to the axis of the web block. 85
5. A pipe wrench including a handle lever, a fulcrum shoe fixed at the end of the lever, the shoe comprising a pair of rigidly connected spaced disks lying on opposite sides of the lever and bolted thereto, a chain pivoted at one end to the lever, and an anchor lug on the lever to detachably engage any free link of the chain after the chain has been passed around a pipe, the anchor link of the chain comprising a pair of plates of arcuate form serrated along their concave edges for biting engagement with the pipe and with their ends pivoted on the ends of the shoe bolt, the length of said plates being considerably in excess of the radius of the disks. 90
6. In a pipe wrench a handle lever and shoe fixed to the end of the lever and adapted to provide a fulcrum at its point of engagement with a pipe and articulated flexible device to encircle the pipe, pivotally connected at one end of the lever, means associated with the handle to be selectively engaged with one of the free links of the articulated device, said shoe and one of the links of the articulated device being serrated to provide spaced pipe gripping members. 95
7. A wrench as set forth in claim 6 and wherein the serrated link is the link which is permanently connected to the lever, said link being of greater length than the remaining links of the flexible device. 100
8. In a pipe wrench a handle and a pipe encircling flexible device associated with the handle and adapted to tighten about the pipe as the handle is moved in one direction and spaced pipe engaging and gripping elements associated with the handle and the flexible device respectively, one of said elements comprising a fulcrum shoe fixed to the handle, the other of said elements comprising a swinging arm pivoted to the fulcrum shoe. 105
9. In a pipe wrench a handle and flexible device to encircle the pipe said flexible device being contractible as the handle is moved in one direction, a pair of spaced pipe gripping elements movable to present different fulcrum surfaces to a pipe and means whereby said elements are caused to firmly engage the pipe as the handle is moved to tighten the flexible device, one of said elements comprising an arcuate arm pivotally connected to the handle at one end and the chain at its other end. 110

Signed at Boonton, in the county of Morris and State of New Jersey, this 15th day of July, 1929.
